UNITED STATES PATENT OFFICE.

ANDREW LANG, OF EDMONTON, ALBERTA, CANADA.

DESIGN FOR AN AUTOMOBILE BODY.

Application filed September 26, 1927. Serial No. 23,547. Term of patent 7 years.

To all whom it may concern:

Be it known that I, ANDREW LANG, a subject of the King of Great Britain, and a resident of the city of Edmonton, in the Province of Alberta, Canada, have invented a new, original, and ornamental Design for an Automobile Body, or which the following is a specification, reference being had to the accompanying drawing, forming part thereof.

In the drawing Figure 1 is a perspective view of an automobile body embodying the design of the present invention and,

Figure 2 is a front end view of the automobile body shown in Figure 1.

I regard the window glass panel as the dominant feature of my design.

I claim:

The ornamental design for an automobile body substantially as shown.

Dated at Edmonton this 10 day of September, 1927.

ANDREW LANG.
